TELEPHONE CABINET

James F. Antonio, 826 S. Osage St., and Floyd L. Antonio,
2250 W. Kentucky Ave., both of Denver, Colo.

Filed Sept. 10, 1959, Ser. No. 57,499

Term of patent 14 years

(Cl. D13—1)

FIG. 1 is a front elevational view of a telephone cabinet showing our new design;

FIG. 2 is a side elevational view thereof;

FIG. 3 is a top plan view thereof; and

FIG. 4 is a vertical cross section therethrough taken on the line 4—4, FIG. 3.

The side not shown is similar to the side shown in FIG. 2. The back is plain. The vertical lining on the drawing represents color. The conventional wording on the drawing is shown in broken line for illustrative purposes.

We claim:

The ornamental design for a telephone cabinet, as shown and described.
